UNITED STATES PATENT OFFICE.

CHRISTIAN L. OTTO, OF GREELEY, COLORADO.

APPARATUS FOR DRYING PHOTOGRAPHS.

1,082,818.

Specification of Letters Patent. Patented Dec. 30, 1913.

Application filed April 1, 1913. Serial No. 758,277.

To all whom it may concern:

Be it known that I, CHRISTIAN L. OTTO, a citizen of the United States, residing at Greeley, in the county of Weld and State 5 of Colorado, have invented certain new and useful Improvements in Apparatus for Drying Photographs; and I do hereby declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

This invention relates to new and useful improvements in devices for drying photographs and comprises a simple and efficient device of this nature having various details 20 of construction and combinations and arrangements of parts which will be herein-after fully described, shown in the accompanying drawings and then specifically defined in the appended claims.

25 My invention is illustrated in the accompanying drawings, in which:—

Figure 1 is an end view of the apparatus, a part being broken away. Fig. 2 is a top plan view. Fig. 3 is a central longitudinal 30 sectional view. Fig. 4 is a detail vertical sectional view through one end of the drying drum and mounting therefor, and Fig. 5 is a sectional view showing a brake mechanism.

35 Reference now being had to the details of the drawings by letter, A designates a suitable frame of the apparatus upon the supports B of which a rotatable drying cylinder C is mounted, said cylinder being hollow 40 and provided with a disk D fastened to each end thereof. To one of said disks is fixed a crank shaft E and to the other end a flanged collar F, shown clearly in Fig. 4 of the drawings, and which latter is mounted 45 in an aperture in one of the supports B of the frame and rotates therein and about a tubular shell H, which latter forms a conduit through which the electric wires I pass. Suitable insulating pipes K are connected 50 to the tubular shell H and through which the wire is passed to any suitable source of supply not shown.

In order to ventilate the interior of the cylinder C, apertures J are formed in the 55 disks at the ends of the cylinder and access

may be had to the interior of the cylinder through an opening regulated by a slide O in one end of the cylinder. An electric heating coil L is mounted within the cylinder, being supported by the pipes N and 60 through which the electric wiring passes to the coil.

A web R, of suitable fabric, is adapted to wind about the cylinder C and upon which web the photographs, designated by letter T and shown in Fig. 2, are adapted to be placed preparatory to their being fed forward between the web and the circumference of the cylinder, as shown by dotted lines in the drawings. Said web passes about a 70 reel or cylinder S, mounted upon a crank shaft S', which latter is journaled in suitable bearings in the frame of the apparatus.

A table P is mounted upon the standard P' upon one of the supports B and affords a 75 convenient means for placing a pile of photographs to be dried or for holding the photographs after being dried.

Referring to Fig. 5 of the drawings will be seen a brake mechanism, consisting of a 80 socket member M, movable within a shell M' in the support B and having a rubber filler M² which is adapted to be held frictionally in contact with the disk D forming one end of the cylinder, through the medium 85 of the spring Q which is fastened at Q' to the support B, the tension of which spring is regulated by an adjusting nut Q² upon the screw Q⁴ and upon which screw the washer Q³ is mounted and against which the nut is 90 adapted to bear.

The operation of my drying apparatus will be readily understood and is as follows:—The heat being supplied to the coil through the electrical connections, the prints 95 are placed upon the web and cylinder C rotated by the crank E, thus winding up the web with the prints intermediate the same and the circumference of the cylinder. A reverse movement imparted to the web by 100 winding the cylinder or reel S will cause the web to travel in the opposite direction and the prints may be removed therefrom.

What I claim to be new is:—

1. An apparatus for drying photographic 105 prints comprising a frame having a hollow rotatable cylinder, a crank shaft fastened to one end of the cylinder and journaled in the frame, a collar fastened to the other end of the cylinder and journaled in said frame, 110

an insulating tube passing through said collar which forms a bearing for the latter, a heating coil within the cylinder, electrical connections passing through said pipe and connected to the coil, a reel journaled in suitable bearings upon the frame, a web adapted to wind about said cylinder and reel, and a 5 web adapted to wind about said cylinder and reel.

2. An apparatus for drying photographic prints comprising a frame having a hollow 10 rotatable cylinder, a crank shaft fastened to one end of the cylinder and journaled in the frame, a collar fastened to the other end of the cylinder and journaled in said frame, an insulating tube passing through said collar 15 which forms a bearing for the latter, a heat-

ing coil within the cylinder, electrical connections passing through said pipe and connected to the coil, a reel journaled in suitable bearings upon the frame, a web adapted to wind about said cylinder and reel, and a 20 spring-pressed buffer brake mounted in the frame and adapted to bear against one end of the cylinder.

In testimony whereof I have hereunto affixed my signature in the presence of two 25 witnesses.

CHRISTIAN L. OTTO.
